UNITED STATES PATENT OFFICE.

GEORGE F. EBEL AND FREDERICK M. ZINK, OF CANTON, OHIO, ASSIGNEES, BY MESNE ASSIGNMENTS, TO THE UNION METAL MANUFACTURING COMPANY, A CORPORATION OF OHIO.

BASE FOR LAMP STANDARDS.

Application filed September 16, 1925. Serial No. 56,751.

The invention relates to metal columns such as are used for lighting standards and more particularly to the cast-iron base which supports the column.

5 In a common form of lighting standards now in use, the cast-iron base which supports the column, is anchored to a cement or concrete foundation by means of anchor rods imbedded in the cement foundation and connected to the upper ends of the base.

When an installation of such lighting standards is made the cement foundations are first poured and the anchor rods imbedded therein. Considerable time usually 15 elapses before the bases are installed, these anchor rods being left protruding two or three feet above the sidewalk; and the same are frequently bent, which not only interferes with their usefulness but makes the 20 same a menace to pedestrians.

In a number of cases persons have been injured by falling over these rods which have become bent across the sidewalk, and clothing is frequently torn by catching upon the 25 threaded upper end portions of the rods.

The object of the present invention is to provide a base ring, which may be octagonal, hexagonal, circular, square or other shape conforming to the shape of the base, this 30 ring being placed directly upon the cement foundation and secured thereto by anchor rods which are only sufficiently long enough to extend through the ring, thereby preventing the possibility of their being bent across 35 the sidewalk and becoming a menace to persons passing upon the same.

A further object is the provision of a shoulder upon the base ring arranged to set within the lower open end of the cast-iron 40 base, each ring acting as a template which, when leveled, causes the standard to set absolutely plumb and which prevents the base from being shifted on the foundation in the event the same is struck by a vehicle.

45 The above and other objects may be attained by constructing the standard in the manner illustrated in the accompanying drawings, in which—

Figure 1 is a vertical sectional view of a 50 lamp standard mounted upon the improved base ring;

Fig. 2, a section on the line 2—2 Figure 1, and

Fig. 3, a detail perspective view of the improved base ring.

55

Similar numerals of reference indicate corresponding parts throughout the drawings.

The usual cement or concrete foundation is shown at 4, the anchor rods 5 being imbedded therein, the upper threaded ends 6 thereof extending only about two inches above the surface of the foundation.

These anchor rods may be of considerably greater diameter than the anchor rods which usually extend to the upper end of the base, 65 it being usually necessary to provide comparatively small anchor rods in order not to interfere with the electric cables and wires or apparatus which is ordinarily located within the base.

70 It has been found by experience that the greatest corrosion in these anchor rods takes place at the point where they enter the cement, and it will thus be seen that there is a considerable advantage in using the heavier 75 anchor rods as the same will have a considerably longer life.

The base ring 7, which may be of any desired shape, conforming to the cast-iron base to be used thereon, is placed upon the cement 80 foundation, the openings 8 thereof receiving the upper threaded ends 6 of the anchor rods, nuts 9 being placed thereon to secure the base ring in position.

85 The ring may be left in this position for any required time before the base is assembled thereon, without danger to pedestrians, as the anchor rods merely protrude through the ring a sufficient distance to receive the nuts and cannot be bent across the sidewalk or path of pedestrians in the manner above referred to with the usual form of anchor rods.

90 The cast-iron base 10 is arranged to be placed upon the ring, a shoulder 11 spaced from the outer edge of the ring engaging 95 the inside of the base and properly centering the same upon the ring. Lugs 12 are formed upon the ring having the inverted T-shaped slots 13 therein to receive the 100 heads 14 of tie-rods 15, the upper ends of which extend through suitable openings 16, in the flanges 17, at the top of the base. These upper ends of the tie-rods are threaded to receive nuts 18 whereby the base is 105 tightly clamped in position upon the ring.

The sheet metal shaft or column 19 may be placed upon the upper end of the base in the usual manner and secured thereto as by the usual tie-rods 20 connected at opposite ends to the upper end of the base and to the cap 21.

From the above it will be seen that the present construction has many advantages over the usual practice above pointed out.

10 When installing a standard this base ring will be the only part of the standard which will be placed on the street until the final installation of the standard is made.

Since it is possible to have heavier anchor rods with this construction, it will be seen that a stronger and more durable structure is provided, because the heavier anchor rods will not corrode as quickly as the lighter ones.

20 In the event the standard is struck by a vehicle, or the like, the base cannot be shifted on the foundation as the shoulder upon the base ring holds the base securely in position. It will also be seen that this 25 ring provides a considerably larger bearing surface on the foundation than is possible with the usual construction where the bottom edge of the base rests directly upon the cement foundation. This provides a 30 much more rigid installation.

Another very important advantage of this construction is in the ease and readiness with which the standard may be repaired after an accident. With the usual construction, having anchor rods extended from the cement foundation to the upper end of the base, it has been found in many instances that one or more of the anchor rods are broken off when the standard is struck. 40 This requires that the entire cement foundation must be torn up and new anchor rods installed, involving not only expense but considerable time to repair the same.

Where such an accident occurs during the 45 day it is very important to the city or lighting company that the repair work be done

immediately in order that the standard may be lighted by dark, and it is obvious that when one of these anchor rods is broken it is impossible to repair the standard within 50 that time.

With the use of the improved base ring the tie-rods 15 may be broken by accident but they can be replaced in a few minutes by merely removing the head of the broken 55 rod from the slotted lug 12 and inserting a new rod.

By using this ring the standard may be completely assembled in the factory or warehouse, requiring only the connection of the 60 base to the ring when the same is installed in the street. This may be easily accomplished through the usual door provided in the base. In a great many instances, especially in extremely cold weather, this is a 65 decided advantage.

We claim:

1. A standard including a base ring, means for anchoring the ring, slotted lugs at the inner edge of the ring, a base resting 70 upon the outer edge portion of the ring and tie-rods engaging said slotted lugs for detachably connecting the base to the ring.

2. A standard including a base ring, means for anchoring the ring, a shoulder 75 spaced from the outer edge of the ring, slotted lugs at the inner edge of the ring, a base resting upon the outer edge portion of the ring, in engagement with said shoulder, and tie-rods engaging said slotted lugs for 80 detachably connecting the base to the ring.

3. A standard including a base ring, means for anchoring the ring, a shoulder spaced from the edge of the ring, slotted lugs upon the ring, a base engaging the 85 shoulder upon the ring and tie-rods engaging said slotted lugs for detachably connecting the base to the ring.

In testimony that we claim the above, we have hereunto subscribed our names.

GEORGE F. EBEL.

FREDERICK M. ZINK.
